UNITED STATES PATENT OFFICE

EDGAR L. JASPAR, OF VENTURA, CALIFORNIA, ASSIGNOR OF ONE-HALF TO WILLIAM D. SHAFFER, OF BREA, CALIFORNIA

MULTICLOSURE HEAD VALVE ASSEMBLY

Application filed July 21, 1930. Serial No. 469,483.

This invention relates to valves and more especially to free floating disc-head valves and seating means therefor.

It is an object to provide an improved valve assembly comprising a seat means and a multi-part closure in which each such closure part is capable of making a complete shut-off of the flow-way in the seat means; whereby to obtain a more effective closing of the flow-way and to secure very long life of the parts.

In deep well drilling practice it is usual to circulate a mud or slush liquid which is highly detrimental to the pumping and circulating apparatus because of the rapid wear occasioned by attrition of grit on the metal parts.

An additional object is to provide closure parts in such relation and of such design that there is produced a seat washing action due to displacement of a body of the liquid trapped between the mutual closure parts which cooperate to form a small trap chamber.

A further purpose is to provide a valve assembly of few, simple and rugged parts; all having a mutual inter-guiding relation.

The invention consists in certain advancements in this art as set forth in the ensuing disclosure and having, with the above, additional objects and advantages, and whose construction, combination and details of means, and the manner of operation will be made manifest in the description of the hereinafter illustrative embodiment; it being understood that modifications, variations and adaptations may be resorted to within the scope, principle and spirit of the invention as it is more directly claimed hereinafter.

The figure is an axial section of the assembly; with parts in closed relation.

In the form shown a seating means includes an annulus 2 adapted to be mounted in a relative support not shown and provides a flow-way 3 for fluid being pumped.

Seatable on the top area of this seat 2 is a closure which consists of a plurality of disc-like closures 4 and 5. The closure 4 has a bottom, marginal face 4^a mutually conforming to a seat zone 2^a of the seat top area 50 and also has guide lugs 4^b to freely reciprocate in the ring 2. Projecting from the top of the closure 4 is a stud 4^c working freely as a guide in and for the upper closure 5.

The upper closure 5 has a hollow stud 5^a 55 over the stud 4^c and also has its lower face concaved at 5^b for reception of the closure 4 and allowing space above it when both closures are seated in the ring 2. The closure 5 has a marginal skirt flange 5^c whose lower face 5^d is complementary to a seating zone 2^d on the seat 2.

It will be seen that both parts 4 and 5 of the valve closure may be fully seated at one time. When the valve is in action either 65 closure 4 or closure 5 may open or may close before the other; each making a full shut off when completely seated. If one closure is prevented from fully seating the other is free to make a full shut-off.

A feature of the valve is that there is a forceful seat cleaning or wash flow between the zones 2^d and 5^d as the trapped fluid is displaced from the upper chamber 5^b by the closing movement of the closure 5 so that 75 this face is kept clean and free of obstructions so that if the inner closure does not make a tight seat then the upper will.

The hollow stud 5^a of the closure 5 is surrounded by a helical spring shown in dotted 80 lines to aid in closing the valve, but not being claimed herein, as this is a conventional element.

What is claimed is:

1. A valve device comprising an annular 85 seating means having a central flow-way, and a closure therefor including multiple closure parts having concentric seating relation on said means, said parts so coacting as to cause a forced wash-flow between the seat 90

area and the closure seating face of the outer closure part.

2. A valve device comprising an annular seating means presenting concentric seat areas merging in a common plane, an inner closure disc having a seating face closing on the inner area, and an outer closure disc closely telescoping over the inner disc and having a seating face closing on the outer area; whereby all of the liquid expressed by the closing outer disc forcibly washes the outer seat area surrounding the inner, seated disc.
